UNITED STATES PATENT OFFICE.

GUY W. BLACKBURN, OF ELGIN, ILLINOIS.

EDGING-MACHINE.

1,101,678.

Specification of Letters Patent. Patented June 30, 1914.

Original application filed March 24, 1911, Serial No. 616,555. Divided and this application filed August 4, 1913. Serial No. 782,790.

To all whom it may concern:

Be it known that I, GUY W. BLACKBURN, a citizen of the United States, residing at Elgin, in the county of Kane and State of Illinois, have invented a certain new and useful Improvement in Edging-Machines, of which the following is a specification, and is based upon the subject-matter contained in and divided out of my copending 10 application, Serial No. 616,555, filed March 24, 1911, for tube-forming machines.

My invention relates to improvements in edging machines such as may be used in connection with tube forming machines and 15 the like for the purpose of bending, upsetting or edging flat tube or can blanks as they proceed toward the tube forming machine. The machine, of course, may be used for other purposes than tube forming but is 20 particularly well adapted for this use.

It is illustrated diagrammatically in one form in the accompanying drawings, wherein—

Figure 1 is a plan view; Fig. 2, a section 25 along line 2—2 of Fig. 1; Fig. 3, a section along line 3—3 of Fig. 1; Figs. 4 and 5 are perspective details of the guides shown in Fig. 1; Fig. 6 is a detail plan view of the lower crimping die shown in Fig. 3; Fig. 7, 30 a section along line 7—7 of Fig. 1; and Fig. 8, a detail in part section of the pusher rod and operating mechanism showing a part of the can forming machinery to which my device is adapted to be applied. Fig. 9 is a 35 section along the line 9—9 of Fig. 6; Fig. 10 is a detail of the crimping roller; Fig. 11 is a section along the line 11—11 of Fig. 10; Fig. 12 is a section along the line 12—12 of Fig. 10.

Like parts are indicated by like references in all of the figures.

The main frame A which is mounted upon the legs A¹ carries the fixed parallel gage bars A² between which are located the adjustable parallel guides A³, A⁴ and A⁵ which are all positioned with respect to the gage bars A² and have the transverse slots A⁷ to engage the holding bolts A⁸. The guide bars A³ have along their inner edges the bearing 45 surfaces A⁹ and guide surfaces A¹⁰, at right angles one to the other, a portion of the upper surface of each guide bar A³ being tapered off at A¹¹ in opposition to the upwardly inclined end A¹² of each guide 50 bar A³ which is mounted upon each bench 55 strip A¹³ which is mounted upon each bench

A¹⁴ on the guide bar A⁴ to form the guiding groove A¹⁵ in the edge of the guide strip A⁴. The end of the guide strip A³ which is adjacent to the guide strip A⁴ is provided with the angular groove A¹⁶ in opposition to the end of the slot A¹⁵. The crimping plates A¹⁷ are spaced by blocks A⁶ with respect to the guide bars A² and provided on their adjacent sides with the curved and tapered guiding slots A¹⁸ which extend to the truncated conical crimping rolls A¹⁹ and are provided beyond said rolls with the angular guide slots A²⁰ in line with the guide grooves A¹⁵ formed by the strips A¹³ in the edge of the guide bars A⁵. The spring actuated latch A²¹ is interposed between the crimping plate A¹⁷ and the guide bar A⁵ and projects outwardly into the line of the grooves A¹⁵.

The guide rail B which is supported at one end in the bracket B¹ on the table A 75 and at the other end in the boss B² on the end frame B³ is located above and between the guides A³, A⁴ and A⁵ and carries, by means of the sliding bearings B⁴, the carriage B⁵ which in turn carries the flat die B⁶ provided with the angular edge B⁷ in opposition to one of the truncated conical rollers A¹⁹. The tracks B⁸ on the bottom of the frame support the carriage B⁹ which carries the die B¹⁰ in opposition to the die B⁶ 80 and is provided with the angular edge B¹¹ in opposition to the other truncated conical roller A¹⁹. The rail B¹² is mounted in the brackets B¹³ on one side of the frame A and has slidably mounted thereon the sleeve B¹⁴ 85 which is rigidly connected to the carriage B⁵ by the arm B¹⁵ and to the carriage B⁹ by the arm B¹⁶. The carriage B⁹ carries the outwardly and upwardly extending spring arm B¹⁷, which terminates in the hook B¹⁸, 90 extending upwardly into the plane of the guide surfaces A⁹ and the die B¹⁰ carries at one end the spring hooks B¹⁹ extending upwardly into the plane of the guide grooves A¹⁵ and at the other end the spring actuated latch-lugs B²⁰.

For the sake of showing how my device is used in connection with one form of machine, I have illustrated some of the parts operating in connection with a cam. They are as follows: The split collar not here shown is in slidable engagement with a mandrel for the purpose of feeding the can. This collar is rigidly attached to the slidably mounted shaft E¹³ which slides in the 105 110

sleeve E¹⁴ in the frame B⁵. This shaft is also slidable in the sleeve E¹⁶ on the bracket E¹⁷. The spring E¹⁹ tends to yieldingly draw the shaft E¹³ toward the left-hand end 5 of the machine as shown in the drawing and resists the longitudinal movement of the shaft in response to the movement of the sleeve E¹⁶ which is caused by the lug E²¹ being pressed upwardly by a spring as 10 shown to engage the sleeve E¹⁶ when the sleeve E¹⁶ has passed to the left beyond the lug E²¹. Thus the forward movement of the carriage B⁵ to the right as it feeds the blank through the edging mechanism also 15 feeds the can forward into the machine so as to leave room for the blank to be fed.

It will be evident that while I have shown in my drawings an operative device, still many changes might be made both in size, 20 shape and arrangement of parts, without departing from the spirit of my invention, and I wish, therefore, that my drawings be regarded as in a sense diagrammatic.

The use and operation of my invention are 25 as follows: A belt, not shown, drives from any suitable source of power the driving pulley on the driving shaft, thus operating the machine. The flat metal blanks which are to be made into tubes are fed into the 30 machine by placing them upon the bearing surfaces between the guide surfaces of the parallel guides on the main frame. The reciprocation of the rod driven by any suitable source of power, since the connecting 35 rod is pivoted to the sleeve B¹⁴, which sleeve is mounted on the drive carriage, reciprocates the drive carriage. Each outward movement of the carriage brings the spring hooks carried thereby into engagement with 40 the rearward edge of one of the blanks. The inward movement of the carriage draws this blank forward beneath the guide strips into the guide slots. The next outward movement of the carriage brings the dies on the 45 carriage into opposition with either side of the blank, the return of the blank being prevented by the slot or groove in the edge of the guide. When the carriage starts its forward movement, the spring hooks on the 50 lower die engage the rearward edge of the blank and carry it forward between the two crimping plates where its edges are slightly curled or bent to and beyond the crimping rolls which crimp or bend the edges against 55 the angular side extension of the die. On the next outward movement of the carriage the blank is caught by the latch on the farther side of the crimping plate and drawn out from between the dies. The 60 next forward movement of the carriage causes the spring actuated latch lugs to engage the rearmost edge of the blank and carry it forward into the machine to a position in opposition to the mandrel. The 65 bracket E¹⁷ is supported on the carriage B⁵.

G¹² is a connecting rod leading from any suitable source of power which reciprocates the yoke B¹⁵ to drive the carriage. With the parts in the position shown in Fig. 8, the sleeve E¹⁶ moves forward carrying with 70 it the rod E¹³ and approaching the sleeve E¹⁴. As this sleeve is approached the latch E²¹ will enter the sleeve E¹⁴ and finally be by its contact with that sleeve thrown out of contact with the sleeve E¹⁶. The rod E¹³ 75 will then be drawn through the sleeve E¹⁶ by the tension of the spring E¹⁹, assuming subsequently the position shown in Fig. 3. The return reciprocation of the sleeve E¹⁶ will cause it to slide along the rod E¹³ 80 until it passes over the latch E²¹, subsequently assuming a position similar to that shown in Fig. 8.

I claim:

1. A blank engaging machine comprising 85 a track, blank edging dies mounted for reciprocation along said track, spring fingers projecting from said dies and adapted to reciprocate therewith to feed blanks along said track, blank engaging projections carried by said dies to engage and feed blanks 90 along said track, and blank bending guides along said track in opposition to said dies.

2. A blank edging machine comprising a 95 track, blank edging dies mounted for reciprocation along said track, spring fingers projecting from said dies and adapted to reciprocate therewith to feed blanks along said track, blank engaging projections carried by said dies to engage and feed blanks 100 along said track, and blank bending guides along said track in opposition to said dies, said dies having one on either side an angular outwardly extending edge in opposition 105 one to each of said blank bending guides.

3. A blank edging machine comprising a 110 track, blank edging dies mounted for reciprocation along said track, spring fingers projecting from said dies and adapted to reciprocate therewith to feed blanks along said track, blank engaging projections carried by said dies to engage and feed blanks 115 along said track, blank bending guides along said track in opposition to said dies, and separate bending rollers one on either side 120 of said dies and in line with said blank bending guides.

4. A blank edging machine comprising a 125 track, blank edging dies mounted for reciprocation along said track, spring fingers projecting from said dies and adapted to reciprocate therewith to feed blanks along said track, blank engaging projections carried by said dies to engage and feed blanks along said track, blank bending guides along 130 said track in opposition to said dies, said dies having one on either side an angular outwardly extending edge in opposition one to each of said blank bending guides, and truncated conical bending rollers one on

either side of said dies in line with said guides and in opposition to the angular edges of the dies.

5. A blank edging machine comprising a track, blank edging dies mounted for reciprocation along said track, spring fingers projecting from said dies and adapted to reciprocate therewith to feed blanks along said track, blank engaging projections carried by said dies to engage and feed blanks along said track, blank bending guides along said track in opposition to said dies, and separate bending rollers one on either side

of said dies and in line with said blank bending guides, said guides, track members and rollers being adjustable in opposed groups to vary the distance between said groups.

In testimony whereof, I affix my signature in the presence of two witnesses this 30th day of July 1913.

GUY W. BLACKBURN.
